A. CORNELL ET AL

GAME

Filed Aug. 9, 1921

FIG 2

FIG 3

FIG 4 INVENTOR.
ELLYN CORNELL
HIRAM C. HAZEN
BY *A. B. Bowman*
ATTORNEY.

UNITED STATES PATENT OFFICE.

ALLYN CORNELL AND HIRAM C. HAZEN, OF SAN DIEGO, CALIFORNIA.

GAME.

Application filed August 9, 1921. Serial No. 490,839.

To all whom it may concern:

Be it known that we, ALLYN CORNELL and HIRAM C. HAZEN, citizens of the United States, residing at San Diego, in the county of San Diego and State of California, have invented a certain new and useful Game, of which the following is a specification.

Our invention relates to a game, more particularly a parlor game to be played by 10 two persons and it is in the form of a board and with contesting members to be played from opposite sides of the middle of said board, and the objects of our invention are: first, to provide an intensely interesting 15 game of this class; second, to provide a novel game and a novel way of playing said game; third to provide a game which is a representation of banking and the ways of keeping the money from the bank; fourth, 20 to provide a game of this class in which the placing of the members is a matter of strategy by the players and fifth, to provide a game of this class which is very simple and economical to construct, easy to learn to 25 play, interesting and instructive.

With these and other objects in view as will appear hereinafter, our invention consists of certain novel features of construction, combination and arrangement of parts 30 and portions as will be hereinafter described in detail and particularly set forth in the appended claims, reference being had to the accompanying drawings and to the characters of reference thereon which form a part 35 of this application in which:

Figure 1 is a plan view of the board, Fig. 2 is a plan view of one of the playing members termed the "Cop"; Fig. 3 is a plan view of another of the playing members termed the "Push penny" and Fig. 4 is a plan view of one of another playing member termed the "Thief."

Similar characters of reference refer to similar parts and portions throughout the 45 views of the drawings.

The board, cop, push penny and thieves are preferably made of thick pasteboard but may be made of any material as desired and are printed on one side as shown.

50 The board 1 is provided with the words "Push penny" on opposite ends, which is the name of the game. The board 1 is also provided with forty large squares 1^a and with sixty-three small squares 1^b positioned 55 at the intersections of the lines at the sides of the large squares 1^a and arranged as

shown best on the board in Fig. 1 of the drawings. It is provided near each corner with very large rectangular sections 1^c and 1^d. The sections 1^c are designated "Hospital" and sections 1^d "First aid," there being one of each on each side of the middle of the board. It is also provided with two large sections 1^e on each side interposed between sections 1^c and 1^d which sections are 60 designated "Jail." It is provided in the center with a circular section 1^f which is designated "Cop" and with a section 1^g on opposite sides thereof on the middle line which are designated "Bank" and with a 65 section 1^h at opposite ends in the middle which are designated "Pocket." The sections 1^f, 1^h, and 1^g are circular in form. Used in connection with the board are the following members: the cop member 2 as 70 shown best in Fig. 2 of the drawings being a rectangular member with the representation of a cop thereon, there being only one of these, a push penny 3 as shown in Fig. 3 of the drawings, of which there are two 75 of different color, the one for one player and the other for the other player and fourteen thief members 4 with the designation of a person in striped clothes and the word "Thief" thereon. There are seven of these 80 for each player, making fourteen, seven being of a different color than the other seven, so that they may be readily distinguished by the players.

The push penny member 3 may be moved 90 in any direction following the lines upon any of the unoccupied small squares 1^b and moved one square in each turn. The push penny cannot jump other members but can be jumped by any of the opposing members 95 except the opposing push penny. The thief member 4 can be moved in any direction following the lines upon any of the small squares that are unoccupied, one square in a turn. It can jump any of the opposing members 100 immediately upon moving into an adjacent square if there is an unoccupied square next beyond the opposing thief member in a straight line. Any members jumped by a thief must be placed in either the first aid 105 or hospital sections on the board on the jumper's side at his choice. A thief can be jumped by any of the opposing thieves and the cop member and if jumped by the cop member it is placed in the jail of the oppos- 110 ing side. The cop member cannot be moved by either player but must jump any member

or members placed in such a manner that there is a vacant square or squares next beyond in straight line. The mover's opponent must jump the cop over the mover's member or any other member or members exposed by the move in such a case. If there is a choice of jumps the player using the cop chooses the way the cop jumps. Thieves jumped by the cop are placed in the jail of the opposite side. The thieves may escape from the jail, first aid, or hospital if the small square in front of the same is unoccupied.

The game is played as follows: the cop member 2 is placed on the cop circle 1^c on the board, the push pennies are then placed at the respective ends of board on the pockets 1^b and each player lines his seven thieves on the seven small squares that form the third row from the middle of the board, counting the middle row, on his side of board. The game is started by one of the players moving one of the thieves or his penny in any direction following the lines upon any unoccupied small square adjacent to the moved thief or push penny, one square in a turn. Upon moving into a square adjacent to an opposing thief or push penny a thief must immediately jump the opposing member or members following the lines in case the square or squares next beyond is unoccupied. If the square next beyond an opposing member is occupied the opposing thief automatically jumps the exposed member or members. A jump does not count as a turn. A thief jumped by an opposing thief is placed in either the first aid or hospital of the jumping side at the discretion of the jumper. If a player moves a member in front of the cop in such a manner as to expose the member, the opposing player must jump the cop over the exposed member or members. In the event there is a choice of jumps the player using the cop has the choice. The cop member can jump but cannot be jumped and cannot be moved by either player except to jump another member as hereinbefore set forth. A thief may escape from the first aid, hospital or jail if the small square in front of the gate is unoccupied, by moving onto the small square, the move counting as a turn in playing. The push pennies cannot jump.

In order to win, a player must either jump the opposing push penny or place his own push penny in one of the banks 1^a on either side.

Though we have shown and described a particular construction, combination and arrangement of parts and portions, we do not wish to be limited to this particular construction, combination and arrangement but desire to include in the scope of our invention the construction, combination and ar-

angement substantially as set forth in the appended claims.

It is obvious that with this construction there is provided a parlor game which is very interesting and instructive; that a great deal of strategy must be used on the part of the players to win; that there are a plurality of points to watch with each play and requires considerable concentration and forethought.

Having thus described our invention what we claim as new and desire to secure by Letters Patent is:

1. A game apparatus including, a board divided into a plurality of square sections, a plurality of small squares positioned at the intersections of the lines of said large sections; a large rectangular section at each corner of the board, a central cop section, two jail sections near the opposite ends near the middle on opposite sides of said cop section, two pocket sections at the opposite ends outside of said jail section, a cop block member, push penny members and seven thief members for each player on opposite sides.

2. A game apparatus including, a board divided into a plurality of square sections, a plurality of small squares positioned at the intersections of the lines of said large sections, a large rectangular section at each corner of the board, a central cop section, two jail sections near the opposite ends near the middle on opposite sides of said cop section, two pocket sections at the opposite ends outside of said jail section, and a plurality of game members movable on said board.

3. A game apparatus including, a board divided into a plurality of square, open sections, a plurality of small squares positioned at the intersections of the lines of said open sections, a large, rectangular section at each corner of the board, a central section, two jail sections near the opposite end near the middle on the opposite side of said central section, and a plurality of game members movable on said board.

4. A game apparatus including, a board divided into a plurality of square, open sections, a plurality of small squares positioned at the intersections of the lines of said open sections, a central cop section, two jail sections near the opposite end near the middle on the opposite sides of said cop section, two pocket sections at the opposite ends outside of said jail sections, and thief, cop and push penny members movable on said board.

In testimony whereof, we have hereunto set our hands at San Diego, California, this 4th day of August, 1921.

ALLYN CORNELL,
HIRAM C. HAZEN.
